UNITED STATES PATENT OFFICE

94,640

DESIGN FOR A SHOE

Karl A. Stritter, Nahant, Mass.

Application December 19, 1934, Serial No. 54,494

Term of patent 3½ years

To all whom it may concern:

Be it known that I, Karl A. Stritter, a citizen of the United States, residing at Nahant, in the county of Essex and Commonwealth of Massachusetts, have invented a new, original, and ornamental Design for a Shoe, of which the following is a specification, reference being had to the accompanying drawing forming a part thereof, in which

The figure is a view in perspective of a shoe showing my design, the outline of the heel and rear end of the shoe being conventional and shown in dot and dash lines.

I claim:

The ornamental design for a shoe substantially as shown and described.

In testimony whereof, I have affixed my signature hereto.

KARL A. STRITTER.
